DOCTOR CLEANING DEVICE

Application filed November 11, 1929. Serial No. 406,276.

This invention relates to the inking of intaglio plates or dies in a machine for fine printing.

The principal objects of the invention are to provide means for reducing the amount of ink used at each operation in a machine of this type; to provide means for cleaning a doctor after each inking operation to remove the surplus ink therefrom; to provide means for engaging the doctor on its inked side at a distance from its scraping edge and moving over the doctor to remove the ink therefrom; to provide means for supporting the doctor behind the scraping device near its edge, and to provide these elements in combination with the usual means for vibrating the doctor while in operation in a machine in which the die or plate is positioned with its printing side up.

Other objects and advantages of the invention will appear hereinafter.

Reference is to be had to the accompanying drawings, in which

Fig. 1 is a side view of an intaglio printing machine, with a preferred embodiment of this invention applied thereto and shown in printing position;

Fig. 2 is a plan of the doctor and shaft for supporting it, as indicated by the arrow 2 in Fig. 1, showing adjacent parts in section;

Fig. 3 is an end view of a part of the doctor vibrating device, as indicated by the arrow 3 in Fig. 1;

Fig. 4 is a sectional view on the line 4-4 of Fig. 1;

Fig. 5 is a vertical sectional view through the press, of the die carriage showing the operation of printing, the parts being in the same position as in Fig. 1;

Figs. 6 and 7 are side elevations of two of the cams employed;

Fig. 8 is a sectional view of the die chuck and associated parts, illustrating the position of the doctor while the first coat of ink is being applied to the die;

Fig. 9 is a similar view showing the die moving in the opposite direction and the doctor in position for removing the surplus ink;

Fig. 10 is a sectional view showing the doc-

tor in the position in which the ink is about to be removed from it, and the means for moving the doctor scraping blade; and

Fig. 11 is a sectional view of the tank for holding the ink removed from the doctor and showing the way in which it is supported.

It is customary to make printing presses of the die stamping type, with the die in the press face up, so that the print is made on the lower face of the sheet as it lies on the feed table of the press. It is also customary to pass the die under a cushioned pad covered with a die wiping paper which removes all the ink from the face of the die preparatory to printing. This system has long been open to serious criticism because a relatively large amount of ink is wasted at each printing operation and also a large piece of die wiping paper is required for each print. These two items represent so large an expense that some efforts have been made to save this waste material. As far as I am aware, these efforts have been mostly in the direction of inverting the die and providing a doctor underneath which slants downwardly and removes the ink from the plate or die and then disposes of it. This however, involves considerable expense to establish in a plant already working on the type of machines first described above. This invention is designed to avoid the necessity of scrapping old machines and putting in the inverted type and to provide for saving the waste ink in the ordinary type of machine and also to save in the amount of wiping paper employed.

Referring to Fig. 5, this shows a machine of the ordinary type with this invention applied thereto. In this machine, there is a die carriage 10 on which is located a chuck 11 in which is mounted the printing plate or die 12. These three parts are reciprocated in the direction of the arrow. When in the position shown the ram 13 rises and the paper located on the die is pressed against the counter 14. The print is made on the lower face of the sheet between the die 12 and the counter 14.

According to this invention, a transverse horizontal shaft 15 is employed which carries a doctor 16. This doctor is so located that it

can act on the die or plate 12 in the manner shown in Fig. 9, while the die is passing back to its printing position. It will be understood that first the die moves as indicated in 5 Fig. 8 with an inking roll 17 in contact with it and the doctor out of contact with it, as shown in that figure. Then when it moves back, the doctor comes down on the plate and scrapes the ink from it on its last motion 10 toward printing position. The ink gathers on top of the lower edge of the doctor 16 and this invention has to do with the removal of that ink before the next inking operation. It is found in practice that the amount of ink 15 left on the doctor 16 is so small that it will not run off and cause any trouble if it is wiped off after each inking operation, although if left on without wiping for several operations, it will begin to drip off and cause trouble for 20 that reason.

For the purpose of operating this machine, two shafts 20 and 21 are used. Although the gearing is not shown herein, it will be understood that these shafts are connected with 25 each other and with the shaft which controls the reciprocation of the die chuck so that they work in a certain sequence. The shaft 20 oscillates while the shaft 21 rotates. The shaft 21 is provided with a gear 22 meshing 30 with a pinion 23 on a shaft which has a crank 24 operating a link 25. This link is connected with an arm 26 fixed on a shaft 27 provided with a fixed arm 28. Therefore, a rotation of the shaft 21 will swing this arm 28 back and forth. When it is swung inwardly 35 toward the frame of the machine, it pushes the shaft 15 with it, and when it swings back, a spring 29 brings the shaft back again. This provides the usual vibratory motion of the 40 doctor. The shaft 15 is supported at both ends in bearings provided in brackets 30 for this purpose.

Fixed on the shaft 15 is an arm 31 carrying a cam roll 32. On the oscillating shaft 45 20 is an arm 33 pivotally connected with a link 34. This link carries a cam 35 and is adapted to operate in a guide 36 in which the link not only moves longitudinally, but can be moved laterally, to a position back 50 of that shown and to the dotted line position in Fig. 1.

At the top of this link 34 is connected a spring 36^a also connected with the top of the arm 31 for holding the roll 32 upwardly as far 55 as it will go and with yielding pressure on the printing plate when in contact with it.

To the top of the link 34 is connected another link 37 which is pivoted to the short arm of a bell crank 38 pivoted on the frame 60 of the machine. This bell crank is normally held down at its front end by a spring 39 and is provided with a pivoted link 40 which is pivotally connected to another bell crank 41 carrying another cam roll 42. On the shaft 65 21 is a cam 43 having two circular arcuate

surfaces at different distances from its center for engagement by the roll 42 and for operating the two bell cranks and controlling them. Obviously the spring 39 forces the roll 42 against the cam 43 when possible.

Now when the parts are in the position shown in Fig. 1, the cam 35 is holding the roll 32 in a position to bring the doctor to the vertical position shown in Figs. 5 and 10. When the arm 33 swings down, the cam 35 goes down with it and forces the roll over the rounded end of the cam to the dotted line position in Fig. 1. Also the link 37 is pulled down as indicated and the link 40 also moved down to move the roll 42 into contact with the cam 43, but at present this is on the part of the cam which has the larger radius. The effect of the cam 35 is to move the doctor far back to an inclined position and the effect of the cam 43 at this time is to hold it in the position shown in Fig. 8 where it does not touch the plate and keep it in that position until the cam 43 rotates around to bring the lower part of its cam surface into registration with the roll 42. This allows this roll to move inwardly further, urged by the spring 39. This results in swinging the link 40 down a little more and moving the link 37, and with it the link 34, backwardly away from the guide surface 36. The real effect, however, is to bring the cam 35 a little back of its dotted line position and to allow the roll 32 to move with it so as to bring the doctor 16 down on the die 12 as shown in Fig. 9. The doctor is held against the inked die by the spring 36^a.

Pivots mounted on brackets 45 carried by the die carriage 10 is a doctor cleaning frame 46. This frame carries a small receptacle or tank 47, which is provided, projecting up from the top, with an inverted L-shaped stop 48 adapted to come up back of the doctor, as shown in dotted lines in Fig. 10, and back up the doctor while it is being cleaned. The tank 47 is held in place on the frame 46 by springs 44.

Also mounted on this frame 46 is a shaft 49. Two arms 50 and 56 are fixed on this shaft. To the arm 50 is pivotally connected a link 51 carrying a rotatable stud 52 to which is secured a bar 53. This bar is also secured to an oscillatable shaft 54 located on the frame 46 and carrying fixed thereto a scraper blade 55. It will be seen that this shaft 54 with its scraper blade can be turned and by the link 51.

On the shaft 21 is a cam 57, which by means of a roll 58, pivoted arm 59, and link 60, operates the arm 56 and the scraper blade 55.

The doctor cleaning frame 46, as previously stated, is pivoted at 61 and is adapted to be raised and lowered about this pivot by a link 62 which is operated by a lever 63, roll 64 and cam 65 on the shaft 21. By raising 130

the frame 46 the scraper blade 55, which is mounted on the frame 46, is also raised.

In operation the situation shown in Figs. 1 and 5 is the printing position. It will be noted that the doctor blade 16 is at a distance from the die 12 and from the inking roll 17. Now after the printing operation is completed the die moves back in the direction of the arrow in Fig. 5 and the doctor blade is moved up by the cam 35 which now moves down in the direction of the arrows on the link 34 and arm 33.

The doctor is held by this cam in a definite position as shown in Fig. 8. At this time the die moves backwardly in the direction of the arrow in Fig. 8 under the inking roller 17 and is inked. It then starts on its forward stroke during which it is also inked by the roller or rather the inking operation continues. Before the die starts back the downward motion of the arm 33 to the dotted line position swings the link 37 and bell crank 38 to the dotted line position and moves the roll 42 against the surface of the cam 43.

While on the larger surface of this cam the doctor is kept in the position shown in Fig. 8 but now, just as the die starts to move forwardly toward printing position, the shaft 21 is timed so that the roll 42 will drop into the depression in the cam 43 which lets the link 40 down still further. The result of this is to push the link 37 to the left and the link 34 also. This draws the cam 35 back slightly from the dotted line position and allows the roll 32 to recede so as to bring the doctor down on the die as shown in Fig. 9. It is held on the die as shown by spring pressure due to the spring 39 instead of being positively held thereon but its position downwardly would also be limited by the cam 43 if it were not against the die 12. In this movement obviously the doctor 16 scrapes the ink off the die and some of the ink gathers on the upper face of the doctor near the scraping edge.

It will be seen that during this period the arm 33 is again rising and by the end of its elevation the roll 32 is snapped over the blunt edge of the cam 35 back to the position shown in Fig. 1 and the parts are brought back to the position in which we started, namely, the printing position, shown in Figs. 1 and 5. The roll 42 is moved away from the cam 43 by the fact that the link 37 is moved to practically horizontal position and the cam 35 thus moves the doctor over to vertical position as shown in Fig. 5, through the action of the spring 36a.

It will be seen that at this point the cams 57 and 65 are working on their circular portions and the doctor cleaning frame 46 is in its lowest or horizontal position bringing the ink receptacle 47 down to the position shown and also the link 60 is in such position as to cause the scraper blade 55 to be vertical or

substantially so. Now during the printing operation the two cams 57 and 65 are swinging around to the position shown in Figs. 6 and 7. This has, of course, two results. The cam 65 swings the doctor cleaning frame 46 upwardly from the position shown in Fig. 10. The stop 48 therefore comes up behind the doctor which is flexible and supports it against movement backwardly on account of the scraper blade.

Also the other cam 57 swings the members 56, 51 and 53 to the position shown in Fig. 10 and through that position to the position shown in dotted lines in Fig. 10. That is, while the scraper blade 55 rises to its maximum position, it is swung over to the dotted line position and then is drawn straight down to scrape the ink from the front face of the doctor and drop it down into the tank 47. This descent of the cleaning frame is accomplished by its own weight, of course being controlled by the cam 65.

In this way it will be seen that the machine is designed to operate according to the present general practice in this art with the die right side up and the printing done on the top of it. Thus no reorganization of the machines on the market is required and no retaining of the operators is necessary. This mechanism also can be placed on the machines now in existence, thus affording an important economy in many plants in two ways: the training of the held and the use of their old machines instead of scrapping them.

The ink removed is disposed of in a very simple way without any danger of its dropping on the machinery anywhere or on the paper. The ink so deposited can be emptied by detaching the tank 47 by moving outwardly its spring support and pouring it back into the ink fountain. Ordinarily the use of a piece of paper for wiping the die after it is scraped by the blade 16 is continued but there is so little ink left on the die that only a small amount of paper is used and there is a saving in that. The saving of the ink removed by the doctor and the saving in the amount of paper used in wiping the plate after each inking operation and before printing constitute two items that represent an important economy in this line of printing. The cleaning of the blade is performed after each inking operation and while the printing is going on so there is no pause for this action to take place and no time lost and there will be no accumulation of ink on the doctor from one inking operation to another. This mechanism can be combined with that of any of the ordinary makes of presses of this character with such modifications as may be required.

Although I have illustrated and described only one form of the invention I am aware of the fact that modifications can be made therein by any person skilled in the art.

- without departing from the scope of the invention as expressed in the claims. Therefore I do not wish to be limited in this respect but what I do claim is:—
- 65 1. The combination with a doctor for removing the ink from a printing plate, of means for moving the doctor to a position in which the active edge of the doctor is at the bottom, and means movable downwardly along the front and rear faces of the doctor for cleaning the ink therefrom.
  - 10 2. In an inking device, the combination with a doctor adapted to remove the ink from a printing plate, of means for moving the doctor to a vertical position in which the active edge of the doctor is at the bottom, means movable along the doctor downwardly on its front face for cleaning the ink therefrom, and means for backing up the doctor at the same time.
  - 15 3. In an inking device, the combination with means for inking a printing plate located with its engraved side up, of a doctor in position for removing the surplus ink from the plate, and means for engaging the forward and rearward surfaces of the doctor and removing the ink therefrom.
  - 20 4. In an intaglio printing press, the combination with means for holding a die or printing plate with its printing side up and reciprocating it horizontally, of an inking roll in position to apply ink to the face of the die, a doctor for cleaning the surplus ink off the die, means for moving over the front surface of the doctor and removing the ink therefrom, and means simultaneously moving along the rear surface of the doctor in registration therewith for cleaning the ink from the rear surface of the doctor.
  - 25 5. In an inking device, the combination with a doctor adapted to remove the ink from a printing plate and means for moving the doctor to a vertical position in which the active edge of the doctor is at the bottom, of a scraper blade, means for moving the scraper blade upwardly to a point above the lower edge of the doctor, and means for then turning the scraping blade toward the doctor, the first named means acting to draw the scraper blade downwardly along the surface of the doctor to remove ink therefrom.
  - 30 6. The combination with a reciprocating chuck for holding an engraved printing die or plate with its face up and means for inking the upper surface of the printing plate, of a doctor, means for turning the doctor into contact with the plate for removing the surplus ink, means for raising the doctor out of contact with the plate during a part of the inking operation, means for turning the doctor down, a scraper blade for removing the ink from the doctor, means for moving said scraper blade to bring it into contact with the doctor above its lower edge, and means
  - 35 7. The combination with a reciprocating chuck for holding an engraved printing die or plate with its face up and means for inking the upper surface of the printing plate, of a doctor, a shaft on which said doctor is fixed, means for turning said shaft slightly to bring the doctor into contact with the plate for removing the surplus ink, means for raising the doctor out of contact with the plate during a part of the inking operation, means for turning the shaft to a position in which the doctor extends down therefrom vertically, a scraper blade for removing the ink from the doctor, means for moving said scraper blade to bring it into contact with the doctor above its lower edge, and means for moving the scraper downwardly along the surface of the doctor to scrape the ink off the lower edge thereof.
  - 40 8. The combination with a reciprocating printing plate and means for inking the printing surface thereof, of a doctor, means for turning said doctor into contact with the plate for removing the surplus ink and raising the doctor out of contact with the plate during a part of the inking operation, means for turning the doctor to a position in which it extends downwardly, a scraper blade for removing the ink from the doctor, means for raising said scraper blade to bring it above the lower edge of the doctor, means for turning the scraper against the inked surface of the doctor, means for moving the scraper downwardly along the surface of the doctor to scrape the ink off its lower edge, and means for engaging the rear surface of the doctor to back it up while the scraper is operating on it.
  - 45 9. The combination with a doctor for scraping the surplus ink from the face of an intaglio printing plate or die, a shaft on which the doctor is fixed, means for vibrating said shaft in an axial direction constantly while it is in operation for removing the ink from the plate, means for turning the shaft to bring the doctor into a vertical position depending from the shaft, a scraper blade for cleaning the ink from the doctor, a frame on which the scraper blade is carried, said frame being pivoted on an axis, and means for raising said frame with the scraper blade in an arcuate path to bring the edge of the scraper blade against the doctor at a point above its scraping edge and for lowering the scraper blade along the surface of the doctor to remove the ink therefrom.
  - 50 10. The combination with a doctor for removing the surplus ink from an intaglio die or printing plate, a shaft on which said doctor is mounted, means for turning the shaft from a position in which the doctor engages the printing plate to a position with the doctor hanging down from the shaft, a frame, a
  - 55 110
  - 60 115
  - 65 120
  - 70 125
  - 75 130

scraper blade carried by said frame, means for lifting said frame to a position in which the scraper blade will rise above the bottom of the doctor, and means for swinging the 5 scraper blade against the doctor, whereby the scraper blade will move down along the surface of the doctor as the frame moves down, to remove the ink from the doctor.

11. In an inking device, the combination 10 with a doctor for removing the surplus ink from an intaglio die or printing plate, a shaft on which said doctor is mounted, means for turning the shaft from a position in which the doctor engages the printing plate to a 15 position with the doctor hanging down from the shaft, a frame hung pivotally, a scraper blade carried by said frame, and movable with respect thereto, a shaft, two cams on said shaft, means operated by one cam for lifting said frame by its pivot to a position in which the scraper blade will rise above the bottom of the doctor, and means operated by the other cam for swinging the scraper blade against the doctor, whereby the scraper blade 25 will move down along the surface of the doctor as the frame moves back, to remove the ink from the doctor.

12. In an inking device, the combination 30 with a doctor and means for turning the doctor to a vertical position with its operative edge down, of a movable frame, a shaft pivoted on said frame, a link connected with said shaft to be operated thereby, a scraper blade connected with the link motion and 35 movable to two positions in one of which it is back away from the doctor and in the other it is up in position for its edge to engage the surface of the doctor on which the ink is collected, means for operating said link motion. 40 and means for moving said frame up and down to cause the scraper blade by said combined operating means to rise and move against the surface of the doctor and then descend vertically to scrape the ink from the doctor.

45 13. In an inking device, the combination with a chuck for supporting a printing plate or die and means for reciprocating said chuck in a direction parallel with the top printing 50 face of the die, of means for inking the die as it reciprocates, an oscillatory shaft, a link connected with said shaft, a guide for the link, a cam on the link, a shaft, a doctor blade for the die mounted on said shaft, a cam roll 55 having its axis fixed with respect to said shaft and adapted to operate the shaft when the cam roll is engaged by said cam due to the oscillation of said arm.

60 14. In an inking device for intaglio printing plates, the combination with means for reciprocating the plate and an inking device for applying ink thereto, of a doctor mounted in position to scrape the ink from the plate, a shaft on which the doctor is located, a rotary cam having two arcuate surfaces, one

lower than the other, a roll adapted to engage the cam, yielding means for forcing the roll against the cam, an oscillating arm, a link connected to said arm, a cam on the link for oscillating the doctor shaft to turn the doctor up away from the printing plate and down on its surface alternately as the arm oscillates and means operated by said cam roll for holding the blade in its two extreme positions. 70

15. The combination with means for reciprocating a printing plate and an inking roll for applying ink thereto both on its forward and backward motions, of a doctor mounted in position to scrape the ink from the plate on its reverse motion after it is inked, a shaft on which the doctor is located, an oscillating arm, a link connected to said arm, a cam on the link for oscillating the shaft and the doctor to turn the doctor up away from the printing plate and down on its surface alternately as the arm oscillates, a rotatable cam having a high and low surface, a bell-crank having a roll thereon adapted to engage the last named cam, means connected with said link for operating the bell-crank to hold it against the cam with a yielding pressure, whereby when the roll is held against its cam, that cam will positively locate the doctor either against the printing plate or in an elevated position away from it 90 according to which surface of the rotary cam this roll engages, and yielding means for holding the roll against this cam. 95

16. The combination with a chuck for supporting a printing plate or die and means for reciprocating said chuck in a direction 100 parallel with the upper printing face of the die, of means for inking the die as it reciprocates, an oscillatory shaft, a link connected with said shaft, a guide for the link, a spring holding the link against the guide, a cam on the link, a shaft, a doctor for the die mounted on said shaft, a cam roll on said shaft, a link extending from the first named link, a bell-crank pivotally connected with the second link, a third link extending from the opposite arm of the bell-crank, a rotary cam, and a cam roll operated by the last named link to engage said rotary cam, whereby the cam will positively determine the position of the doctor blade with respect to the printing 110 surface of the die. 115

17. In an inking device, the combination with a doctor adapted to remove the ink from a printing plate, of a scraper blade, means for moving the scraper blade to a point above the lower edge of the doctor, and means for turning the scraping blade toward the doctor, the first named means acting to draw the scraper blade along the surface of the doctor 120 to remove ink therefrom. 125

In testimony whereof I have hereunto affixed my signature.
